SHOE AND SOLE THEREFOR

Arthur Bates, Leicester, England, assignor to
 United Shoe Machinery Corporation, Paterson,
 N. J., a corporation of New Jersey

Application November 28, 1933, Serial No. 700,110
 In Great Britain December 1, 1932

8 Claims. (Cl. 36—12)

This invention relates to shoes and to soles therefor. The invention is hereinafter described with reference to shoes embodying soles having upstanding rims formed thereon.

5 One object of the invention is to provide an improved form of shoe which has certain desirable properties in particular, the junction between upper and sole being at the forepart of the shoe located at a level markedly above the tread 10 face of the sole, it being less easy for dampness from the ground to penetrate through this junction to the foot of the wearer than it is in the case of shoes of ordinary construction.

In this illustrated embodiment the rim of the 15 outsole is so formed that it reaches a maximum height (say perhaps a height approaching three quarters of an inch) above the level of the tread surface of the outsole at the toe portion and gradually decreases in height at each side of the shoe 20 in the direction of the heel until it disappears altogether at about the forward end of the shank portion of the sole at each side of the shoe, the portion of the outsole heelwardly therefrom being of normal form, that is not provided with a 25 rim or outturned marginal portion.

In the construction of this shoe the main body 30 of the upper is lasted inwardly over an insole but the margin of an additional vamp portion of the upper at the forepart of the shoe is turned outwardly and sewn to the said outwardly turned marginal flange on the outsole. It will thus be realized that at the toe portion of the shoe the external joint between upper and outsole is located at a level well above that of the tread of the sole. 35 At each side of the shoe the level of the joint gets lower until at the shank at each side of the shoe it becomes almost that of the tread of the sole. However at the major portion of the forepart of the shoe the said joint, being raised upwardly

40 from the tread will not be so liable when the shoe is in wear to be penetrated by damp when the wearer is walking over wet ground as would a shoe of normal type in which the corresponding joint is substantially on a level with the tread 45 since it is raised above the wetness on the ground and thus such wetness has little opportunity to work its way through into the interior of the shoe.

Moreover since in this embodiment of the invention the said joint at the forepart between 50 upper and outsole is angularly inclined to the horizontal, being, as already explained, at its highest at the toe and decreasing gradually in height towards the heel, any water getting into the crease at the joint will not tend to remain there as it would in the ordinary case where the

corresponding crease is more or less horizontal, but will tend to run off heelwardly and thus is very much less likely to penetrate into the interior of the shoe than it would be if the crease were horizontal in which case it would be likely 5 to lie for some time in such crease.

Another embodiment hereinafter described is a shoe comprising an upper having its margin turned outwardly all round and secured to a sole which is flat at its heel portion and has, around 10 its forepart portion only, an upstanding rim. In this embodiment, which provides a shoe which may be very simply manufactured at low cost and which is particularly suitable for children's wear, the sole is molded to have an upstanding rim 15 of substantially constant height around its forepart portion only, the heel portion being left flat and unmolded. The rim is provided with an out-turned flange. The upper has its margin turned outwardly all round. Round the forepart the 20 out-turned margin is sewn to the flange on the sole while round the remainder of the shoe the outturned margin is sewn to the sole after the fashion commonly practised in making stitch-down shoes. In this embodiment as in the em- 25 bodiment previously mentioned the seam between upper and sole is located at a level markedly above the tread face of the sole at the forepart of the shoe (which is usually the portion of a shoe most prone to admit dampness) and this renders 30 the seam less accessible to and so less likely to be penetrated by ground dampness than is the case with shoes of the more usual constructions.

The above and other objects and features of the invention will become clear from the following description given with reference to the accompanying drawings of the two embodiments of the invention already referred to.

In the said drawings:

Fig. 1 is a side elevational view of a completed 40 shoe constituting an embodiment of the invention;

Fig. 2 is a bottom plan view of the shoe shown in Fig. 1 at a stage in its construction before the outsole is attached thereto;

Fig. 3 is a perspective view of the outsole for the shoe shown in Fig. 1;

Fig. 4 is a cross-sectional view along the line IV—IV of Fig. 1;

Fig. 5 is a side elevational view of a completed 50 shoe constituting a second embodiment of the invention; and

Fig. 6 is a cross-sectional view along the line VI—VI of Fig. 5.

The shoe illustrated in Figs. 1 to 4 of the 55

drawings will first be described. This shoe is particularly useful for sports and other purposes where the wearer may have it constantly in use over wet ground. The upper 1 of the shoe is 5 conveniently made of fairly heavy upper leather which preferably has been treated in well known manner to render it as waterproof as possible. The loose upper 1 (which except as now to be indicated is of normal form) has associated there- 10 with a lining 3 (Figure 4) and has attached to its external surface an additional vamp portion 5 which is secured by a line of stitching 7 to the upper 1 but which is left free around the remainder of its margin. The additional vamp 15 portion 5 is shown as comprising two portions stitched together one of which constitutes a toe-cap. The upper is assembled on a last with a plain insole 9 (that is an insole of the kind used in McKay type shoes) and with a counter 11 and 20 box toe 13 and is then pulled over and lasted to the insole by any of the ordinary methods employed in the construction of McKay type shoes, lasting tacks 15 being illustrated in Figure 2.

During the lasting operation the additional 25 vamp portion 5 is turned out of the way and is not attached to the insole 9.

The outsole 17 for the shoe is seen in perspective in Figure 3 and is molded to the shape seen in that figure by making use of two suitably 30 shaped co-operating sole molds in a sole molding machine of any well known construction. The outsole has round the forepart only an upstanding rim 19 which makes an angle approaching a right angle with the tread face of the sole.

35 The rim 19 is moreover provided with an out-turned flange 21 which itself makes an angle approaching a right angle with the rim. The rim is of maximum height (this, in the illustrated embodiment, being about three quarters of an inch) at the toe end and decreases to zero-height at about the forward end of the shank portion of the sole at each side of the sole. When the outsole 17 is laid on the shoe bottom the forepart portion of the shoe bottom is received in the cavity bounded by the rim 19, the sole being so molded 40 that, as will be seen from Fig. 4, the rim 19 closely embraces the sides of the shoe.

A suitable shank piece (not shown) may be attached to the shoe bottom and any bottom filling 50 23 (Fig. 4) that may be required applied before the shoe and outsole 17 are assembled together. The outsole 17 may be permanently attached to the shoe at the shank at each side by any suitable well known process. For example 55 it may be machine sewn by stitches penetrating right through the insole, or it may be screwed or riveted. At its heel portion it is conveniently nailed down in well known fashion. At the forepart however the outsole is attached in the following manner. The additional vamp portion 5 of the upper of the shoe, which as aforesaid has conveniently previously been turned out of the way is now brought into position with its margin outwardly turned and adjacent the out-turned 60 flange 21 on the outsole. The shoe is then presented to a sewing machine, such as is described in my prior United States specification No. 1,198,405, provided with upper gripping pincers and the additional vamp portion 5 of the upper 65 is progressively pulled into lasted position and sewn by a row of stitching 25 to the flange 21 of the outsole, the stitching 25 passing more or less perpendicularly through the flange 21 and the out-turned margin of the upper.

70 In some instances however it may be found

that the additional vamp portion 5 falls into position so readily that it is not essential that a sewing machine provided with lasting pincers should be employed to sew it to the flange 21. When the additional vamp portion has been sewn 5 to the flange 21 on the outsole, the outsole having previously been secured to the shoe bottom at its shank and heel portions will be firmly attached to the shoe around its whole margin. The shoe will then have its heel 27 attached and will be finished in any ordinary manner.

As has been already indicated hereinbefore it will be more than ordinarily difficult for dampness to penetrate to the interior of a shoe constructed as just described in ordinary wear of 15 the shoe. If desired the degree of waterproofness of the shoe may be yet further increased by coating the internal surface of the outsole (or the portion of the shoe bottom which is to contact with this surface or both) before the outsole is 20 laid on the shoe with wax or other water resisting material, a particularly thick coating being applied at the upper surface of the flange 21 in order that the joint between the flange and the additional vamp portion 5 of the upper shall be 25 rendered as impenetrable to damp as conveniently can be done.

The shoe shown in Figs. 5 and 6 is of the sandal variety and may be very cheaply constructed. It is particularly suited for children's wear. The 30 outsole 29 is molded so that it has round the forepart only an upstanding rim 31. The rim 31 is of substantially constant height from the toe end of the sole to the forward end portion of the shank at which portion it disappears entirely and the shank and heel portions of the sole are flat and unmolded. The rim 31 is provided, like the rim 19, with an out-turned flange 33 which makes an angle in the neighborhood of a right angle with the rim. The upper 35 for the 40 shoe is conveniently formed in one piece (except for the provision of a separate strap 37) shaped to have two side portions which are secured together by a back seam 39. This type of shoe need not necessarily be provided with any 45 box toe though it is desirable to provide a counter which may be stitched to the upper by a line of stitching 41. The outwardly flanged margin of such a counter may be seen at 43 in Figure 5. The loose upper and sole are conveniently 50 assembled together without making use of any last and the outwardly turned margin of the upper is sewn to the sole on a suitable sewing machine, for example a straight needle sewing machine, the stitching being shown at 45 in Figure 55 6. After the securing together of upper and sole the shoe has a single lift heel 47 slugged or nailed thereon and is finished in any desired fashion. A light sock 49 is desirably adhesive- 60 ly secured to the inside surface of the sole.

Having thus described my invention, what I claim as new and desire to secure by Letters Patent of the United States is:—

1. A shoe comprising an upper and a sole having an upstanding rim formed thereon of maximum height at the toe end and gradually decreasing in height from the toe to the forward end of the shank of the shoe, to the peripheral portion of which rim the upper is secured. 65

2. A shoe comprising an upper and a sole having an upstanding rim formed thereon of maximum height at the toe end and gradually decreasing in height from the toe to the forward end of the shank of the shoe said rim having an 70 75

out-turned flange to which an out-turned marginal portion of said upper is secured.

3. A shoe comprising an insole, a continuous upper having a portion lasted inwardly over said insole around the whole periphery thereof, an outsole having an upstanding rim formed thereon around its forepart portion only, said rim having an out-turned flange, and another layer of material covering the vamp portion only of the upper and secured in outturned relation to the upstanding rim.

4. A shoe comprising an insole, an upper having a portion lasted inwardly over said insole around the whole periphery thereof, an outsole having an upstanding rim formed thereon around its forepart portion only, said rim having an out-turned flange, and an additional vamp portion overlying the vamp portion of said upper and having its margin secured to the out-turned flange of the rim of the sole.

5. A shoe sole having an upstanding rim of maximum height at the toe end which decreases gradually to zero height at the shank and heel portions.

25 6. A shoe sole having an upstanding rim of maximum height at the toe end, which decreases gradually to zero height at the forward extremity

of the shank portion and is provided with an out-turned flange.

7. In a shoe, an insole, an upper comprising a layer having vamp and quarter portions and a continuous additional outer layer extending from substantially the front extremity of the shank forwardly, and a sole the shank and heel portions of which are flat and the forepart of which has an upstanding rim having an outturned flange, said vamp and quarter being lasted over upon the insole all the way around the shoe, and said additional layer having its margin out-turned and secured to said outturned flange, the shank and heel portions of the sole being secured in contact with the overlasted upper.

8. A shoe having a full-length insole, an upper comprising quarter and vamp portions lasted inwardly over the bottom of said insole, an outsole comprising a flat shank and heel part and a forepart having an upstanding rim extending about the forepart of the insole, the top portion of said rim being outturned to form a flange, and a continuous layer of material overlying the forepart portion only of the vamp and secured in outturned relation to said flange.

ARTHUR BATES.
